HEAT TRANSFER EQUIPMENT OF THE TUBE
AND HEADER COIL TYPE

John W. Throckmorton, Wilton, Conn., assignor
to Petro-Chem Development Company, New
York, N. Y., a corporation of Delaware.

Application October 17, 1940, Serial No. 361,516

1 Claim. (Cl. 285—20)

This invention relates to heat transfer equipment particularly of the pipe coil and connecting header type used extensively in the processing of oil in refineries, in which use the coils project through and are supported by tube sheets and the return headers or fittings are disposed at the outer sides of such sheets. It is also usable in connection with such equipment applied to tar coolers, drip condensers, and the like, wherein merely a rack or frame work for carrying the weight of the tubes and headers and to maintain the proper spacing may be employed in place of tube sheets.

In the use of heat transfer equipment of this type, it is necessary to arrange the coil tubes and headers or return bends so that they may be properly inspected and cleaned. The oil may corrode such parts, and it is therefore imperative that means of inspection and measurement there-of be provided. The coils may also become clogged with coke formed in the refining process, and this makes it necessary to provide a convenient means for permitting the removal of this coke at the cleaning and inspection periods.

In the designing and use of convection banks of furnaces, as well as other types of tubular heat transfer equipment, it is recognized that it is often very desirable to have a high mass velocity over the outside of the tubes which may be accomplished by placing the tubes on close centers. With such close centering it is not only possible, under certain conditions, to increase the mass velocity over the heating elements, but also to increase the transfer rate per degree of mean temperature difference, and reduce the amount of heating surface for the same overall performance.

The primary object of the present invention is to provide a novel tube and header arrangement and connections for heat transfer equipment of the class described, which permits closer centering of the tubes than is now possible or practicable, so that the advantages incident to such close centering may be obtained. Heretofore it has been the practice, so far as I am aware, to connect the tubes to the headers by rolling. It is found, however, that materially closer tube centers can be obtained if, in connecting a pair of tubes to a header or return bend, one tube is connected to the header by a rolled joint and the other by a welded joint, thus enabling the centers to be reduced to the extent made possible by the permissible reduction of the material of the header at the welded joint over that required for the rolled joint.

A further object of the invention is to provide

for the efficient, convenient and proper cleaning out and inspection of the coil tubes and connected headers or return bends of such equipment without interfering with or preventing the close tube centering feature of the invention.

A further object of the invention is to so construct the header or return bend and connect the tubes of a pipe coil thereto as to cause a true, smooth streamline flow through the header and past the tube joints therewith, so as to reduce to a minimum turbulence of the stream in its passage through the header past the points of jointure of the tubes therewith, thereby materially reducing objectionable corrosion and pressure drop in the equipment at such points.

Other objects and advantages of the invention will be apparent from the following detailed description, and from the accompanying drawing illustrating the invention, in which—

20 Figure 1 is a portion of a pipe coil including a plurality of connected tubes and headers, embodying the invention, and with the header or return bends disposed without the tube sheets; Fig. 2 is an enlarged central vertical section taken 10 lengthwise of a header like shown in Fig. 1, with two tubes connected thereto, one being rolled and the other welded; Fig. 3 is a central cross-section taken 15 in the equipment at such points.

20 Figure 1 is a portion of a pipe coil including a plurality of connected tubes and headers, embodying the invention, and with the header or return bends disposed without the tube sheets; Fig. 2 is an enlarged central vertical section taken 10 lengthwise of a header like shown in Fig. 1, with two tubes connected thereto, one being rolled and the other welded; Fig. 3 is a central cross-section taken 15 in the equipment at such points.

25 In the drawing, the pipe coil is shown as being composed of a plurality of tubes 1 disposed in transversely spaced parallel relation and connected in pairs at their ends by headers or return bend fittings 2, so as to form a continuous coil through which oil, or other liquid being treated may be circulated. The tubes 1 are shown 30 as being supported in tube sheets 3 and the fittings 2 are disposed without such sheets. In this form of the invention, each header 2 preferably has a welded connection 4 with one tube, 35 preferably the inlet tube with respect to such header, and a rolled connection 5 with the other tube, and the clean-out opening 6 for the header, only one of which is provided, is disposed in substantially coaxial alignment with the rolled-in 40 joint. With this arrangement it is apparent that each tube has a welded connection at one end and a rolled-in connection at the other end with the respective headers.

45 It will be noted by reference to Fig. 2 that in this form of header, the disposition of the welded joint at the outlet side of the header enables such end of the passage through the header to provide a smooth, streamlined flow without any interrupting joint and that shoulders, recesses and pockets tending to cause turbulence of the stream

are disposed only at the inlet side of the header passage and at its point of rolled-in connection with the outlet tube. It is found in practice that where a header has rolled connection with both pipes of a pair the most severe corrosion takes place at the inlet end of the pipe and that such corrosion is negligible at the outlet end of the pipe; also, that, if the inlet end of the tube is welded to the header, the high turbulence and consequent corroding action and drop in pressure of the stream due to the rolled joint will be avoided and a smooth streamline flow obtained. This advantage is augmented by providing the header with a single cleanout opening which is disposed in line with the rolled-in tube at the inlet end of the header (the outlet end of the tube).

The cleanout opening 6 may be closed by a plug 7 held in seated position in any suitable manner, for instance by a screw 8 threaded through a cross member 9 removably anchored in openings provided in transversely opposed upright ears 10 on the header. The provision of this opening, in addition to permitting rolling in of the tube, permits the removal of accumulated coke therefrom and also permits inspection and measurements to be taken of the parts where corrosion may occur.

Another important advantage of providing a welded joint between a header and one of the tubes which it connects is to enable closer centering of the connected tubes due to less material being required at the welded end of the header to support welding than is required at the other end to withstand the strains incident to rolling in of the tube. By reason of this closer centering of the tubes in the header, it is possi-

ble to increase the mass velocity over the heating elements, thereby increasing the transfer rate per degree of mean temperature difference and reducing the amount of heating surface for the same overall performance. These are important items under certain conditions in the designing and use of convection type furnaces and also of other types of tubular heat transfer equipment.

10 I wish it understood that my invention is not limited any specific construction, arrangement or form of the parts, as it is capable of numerous modifications and changes without departing from the spirit of the claim.

15 Having thus described my invention, what I claim as new, and desire to secure by United States Letters Patent, is:

20 In a heat transfer coil of the type set forth, wherein a pair of tubes are interconnected, a substantially U-shaped tubular header for interconnecting the tubes, one leg of the header being of a length greater than that of the other and extending outwardly beyond the curve of the header for a distance sufficient for having a rolled joint connection with one of the tubes, and the other and shorter leg terminating at its inner end intermediate the ends of the first leg and closely adjacent to the curve of the header and being welded to the other tube, said header having a single access opening in alignment with the first mentioned tube whereby to lessen the material at the welded end of the header and thereby provide closer centering of the connected tubes, and increase of the mass velocity of the heating elements.

35 JOHN W. THROCKMORTON.
